[57] CLAIM

The ornamental design for a jar, as shown and described.

DESCRIPTION

FIG. 1 is a front elevational view of the jar illustrating our new design;

FIG. 2 is a back elevational view thereof;

FIG. 3 is a left elevational side view thereof;

FIG. 4 is a right elevational side view thereof;

FIG. 5 is a top elevational view thereof; and,

FIG. 6 is a bottom elevational view thereof.

The broken line showing of a screw cap and threaded end are for illustrative purposes only and forms no part of the claimed design.
